UNITED STATES PATENT OFFICE.

ANDREW ALFSON AND HARALD JANSEN, OF CHICAGO, ILLINOIS; SAID
ALFSON ASSIGNOR TO LOUIS ARNESEN, OF SAME PLACE.

SIDE-LOCKING GALLEY-STICK.

SPECIFICATION forming part of Letters Patent No. 463,325, dated November 17, 1891.

Application filed December 12, 1888. Serial No. 293,412. (No model.)

To all whom it may concern:

Be it known that we, ANDREW ALFSON and HARALD JANSEN, citizens of the United States, residing in the city of Chicago, county of Cook, 5 and State of Illinois, have invented a new and useful Side-Locking Galley-Stick, of which the following is a specification.

Our invention relates to improvements in galley-sticks in which by means of a simple locking device the same is easily and securely locked against the inner side of the galley-frame; and the object of our invention is to provide a locking device for the galley-stick in the galley which shall be secure and simple. 10 We attain this object by the mechanism illustrated in the accompanying drawings, in which—

Figure I is a full view of our side-locking galley-stick when locked to the side of the 15 galley. Fig. II represents a side view of the galley-stick, showing the rack in the groove. Fig. III represents side view of bar D. Fig. IV is a sectional view of the rack, showing the pinion and the arms l and l'.

Similar letters refer to similar parts throughout the several views.

In our drawings, A represents the oblong tray or printer's galley.

a is the top ledge and a' a' are the side 20 ledges of the galley.

B represents the galley-stick, which is provided with the groove b. Stick B is in one end provided with the claw c, which hooks over the lower end of the plate of galley A, as illustrated in the drawings. The other end of 25 galley-stick B abuts against the inside of the end of the tray and is provided with an arm extending outward over and beyond the latter, as seen in Fig. II. In the end of this projection is pivoted an eccentric C, which is provided at its outer or lower end with a lip d, as illustrated in said figure. When the stick is put in place, it is fastened by turning down the eccentric against the end of the galley, which brings the lip d underneath the bottom of this end of the tray, and so holds the stick from moving in any direction.

D is a bar which serves as end-lock for the galley-stick. It is in one end provided with

groove d' and shoulder d'', by means of which it slides to and fro upon the upper side of the grooved galley-stick B, as illustrated in our drawings.

d' is a pivoted dog on the side of bar D, by means of which the bar D is locked to the 55 galley-stick B at any desired place.

Within the groove b of galley-stick B, and toward the end thereof to be secured to the top ledge a of the galley, is the straight toothed bar or rack f, which engages with the 60 semi-pinion g. The axis of the pinion g passes through the sides of the flanges forming the groove in galley-stick B, and to the upper end of this axis is secured the finger h, as illustrated. The upper flange of groove b, where 65 the axis of the pinion g passes through the same, is provided with a semicircular plate K, which plate is notched in its upper side near its circumference, as illustrated in our drawings. These notches engage with the 70 finger h.

Within the groove b are the arm l, suitably pivoted in one end at n to the lower flange of the groove b, and arm l', suitably pivoted in one end to the rack f, as illustrated in Fig. II 75 of the drawings. The remaining free ends of the arms l and l' are pivoted together by means of pin m. o is a notch in the upper flange of groove b to receive the projecting end of pin m, as seen in Figs. I and II. 80

The operation of our invention is as follows: Let x represent the type to be locked on the galley, as illustrated in our drawings. We put the galley-stick to the side thereof, so that claw c will hook over the lower end of the 85 plate of galley A. Then we secure the upper end of the galley-stick by means of the dog C to the upper ledge of the galley. Next the galley-stick is pushed against the type. The bar D is moved up against the end of the type 90 and fastened by means of the dog d'. Then the pin m is pushed out of its notch up to the side ledge a' of the galley, whereby the rack is drawn toward the fastening-point of arm l in the lower flange of the groove. When the 95 pin m reaches the side ledge of the galley, the finger h is turned up toward the right from its position, as indicated in Fig. I of our draw-

ings, whereby the pinion *g* is made to engage with the rack *f*, thus further pressing upon arms *l* and *l'* and locking the type.

5 Finger *h* is held in position by the notches of the plate *K*.

What we claim as our invention, and desire to secure by Letters Patent, is—

1. In a device for a side-locking galley-stick, a grooved stick provided with a sliding rack *f*, the pinion *g*, and arms *l* and *l'*, substantially as and for the purpose herein set forth.

2. In a side-locking galley-stick, the galley *A*, in combination with the grooved stick *B* and the eccentric *C*, pivoted to the projecting end of the stick and provided with a lip *d*, adapted to be turned under the end of the galley, substantially as described.

3. In a side-locking galley-stick, the galley

A, in combination with the grooved stick *B*, provided at one end with the claw *c*, the eccentric *C*, pivoted to the other end of the stick and provided with a lip *d*, adapted to turn under the end of the galley, and the bar *D*, substantially as described.

4. A side-locking galley-stick comprising the grooved stick *B*, the plate *K*, the claw *c*, the dog *C*, the bar *D*, the rack *f*, the pinion *g*, the finger *h*, the arms *l* and *l'*, the pin *m*, and the slot *o*, substantially as and for the purpose herein set forth.

ANDREW ALFSON.
HARALD JANSEN.
